UNITED STATES PATENT OFFICE.

HENRY S. KRATZ, OF DANBORO, PENNSYLVANIA.

SHIRT.

1,306,228.

Specification of Letters Patent. Patented June 10, 1919.

Application filed July 19, 1917. Serial No. 181,633.

To all whom it may concern:

Be it known that I, HENRY S. KRATZ, a citizen of the United States, and a resident of Danboro, in the county of Bucks and 5 State of Pennsylvania, have invented an Improvement in Shirts, of which the following is a specification.

My invention relates to improvements in shirts, and it consists in the combinations, 10 constructions and arrangements herein described and claimed.

An object of my invention is to provide a shirt which is comparatively simple in construction, and which is so constructed that 15 it will not bunch about the hips and thighs.

A further object of my invention is to provide a shirt so constructed that the sides are free to hang in extended position in the trousers.

20 A further object of my invention is to provide a shirt having tail portions which are not inclined to work upwardly.

Other objects and advantages will appear in the following specification, and the novel 25 features of the invention will be particularly pointed out in the appended claim.

My invention is illustrated in the accompanying drawings, forming part of this application, in which—

30 Figure 1 is a view showing the shirt in position on the body of the wearer.

Fig. 2 is an enlarged section on the line 2—2 of Fig. 1.

35 Fig. 3 is a perspective view of the shirt looking from the front.

In carrying out my invention I provide a main body portion 1 having sleeves 2 and a neck band 3, the body portion, sleeves, and neck band being of the usual construction.

40 As will be seen from the drawings the body portion does not have the usual side slits but is provided with front slits 4 and 5 and with rear slits 6 and 7. The portion 8 between the front slits 4 and 5 forms a flap

45 while the portion 9 between the rear slits 6 and 7 also forms a flap of the same length and width as the flap 8. The flap 8 is provided with button holes 11.

From the foregoing description of the various parts of the device the operation there- 50 of may be readily understood.

The shirt may be open in front, as shown at 12, or at the rear, in order to get the garment over the head. When the shirt is in position the flap 8 is brought to the rear and 55 the flap 9 is brought forwardly and buttoned to the flap 8 in the manner shown in Fig. 2. This removes these parts out of the way and permits the sides of the shirt to conform to the hips and thighs, that is to 60 say to hang down in a natural position, as shown in Fig. 1, thus obviating bunching of the garment within the trousers.

A shirt made in accordance with my invention does not have the tendency to come 65 up, because of the fact that it is not bunched. Furthermore, the flaps 8 and 9 tend to keep the garment in position.

I claim:

As an article of manufacture, a shirt hav- 70 ing a body portion with continuous side por- tions and provided at its front with a pair of upwardly extending slits and at its rear with a corresponding pair of upwardly ex- 75 tends slits, the portion between the slits of each pair constituting flaps, whose lower edges when released coincide with the lower edges of the continuous side, and which flaps may be overlapped and secured together, and when so secured will lie substantially above 80 the lower portions of the continuous sides, such lower portions of the continuous sides being substantially longer than the flaps when overlapped and terminating in the same line with the lower end of the flaps 85 when the latter are pendent, the side por- tions thus operating to stay the garment in position when the flaps are overlapped and secured together in use, all substantially as and for the purposes set forth.

HENRY S. KRATZ.
